US0D1038781S

(12) **United States Design Patent** (10) **Patent No.:** **US D1,038,781 S**
(45) **Date of Patent:** **** Aug. 13, 2024**

(54) **THERMOMETER**

(71) Applicant: **Cue Health Inc.**, San Diego, CA (US)

(72) Inventors: **Clint Sever**, San Diego, CA (US);
Raphael Shapiro, San Diego, CA (US);
Kevin Wu, San Diego, CA (US);
Michael Credelle, San Diego, CA (US);
Randall Hill, San Diego, CA (US);
John P. Taylor, San Diego, CA (US);
Jay Greenwood, San Diego, CA (US);
Omar Fontes, San Diego, CA (US)

(73) Assignee: **CUE HEALTH INC.**, San Diego, CA (US)

(**) Term: **15 Years**

(21) Appl. No.: **29/882,853**

(22) Filed: **Jan. 19, 2023**

(51) LOC (14) Cl. **10-04**

(52) U.S. Cl.

USPC **D10/57**

CLAIM

We claim the ornamental design for a thermometer, as shown and described.

DESCRIPTION

FIG. 1 is a top, front, right perspective view of a thermometer;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof;

FIG. 7 is a rear elevational view thereof; and,

FIG. 8 is a cross-section view thereof taken along line 8-8 of FIG. 6.

The broken lines are included for the purpose of illustrating portions of the thermometer and form no part of the claimed design.

1 Claim, 7 Drawing Sheets
